ADENOTOME

Charles R. Storz, Indianapolis, Ind.

Application June 17, 1933, Serial No. 676,408

6 Claims. (Cl. 128—309)

This invention relates to an instrument for removal of adenoids, commonly known in the medical and surgical professions as an adenotome, and has reference more particularly to a hand-operated instrument for ready clean removal of adenoid tissues which as is well known is superimposed upon unyielding tissues which has no constant contour or angle in different individuals.

10 An object of the invention is to provide an improved instrument for the removal of adenoids which shall be so constructed as to be flexible so that when pressed forward it shall conform to the angle presented in the individual patient and insure that a clean removal of adenoid tissues shall result in operation and eliminate faulty operation inherent in the rigid type of adenotome hitherto commonly used, which instrument, though capable of being manipulated after being put into position, to include maximum amount of tissue from one individual, but such adjustment is always limited by the spread between the teeth of an open mouth and the fact that neither the instrument nor posterior wall will yield to pressure found by experience to be required in order that clean removal of adenoid tissues shall result, as evidenced by the frequency of re-growth after operation.

Another object is to provide a flexible adenotome or instrument for removal of adenoids which shall be flexible so that when pressed forward shall conform to various angles in different individuals, which instrument shall be so constructed as to have a difference in tension between elements of the instrument, so that the entire adenoid from base to tip shall be removed completely.

A further object is to provide an improved adenotome in which the blade of the instrument shall be prevented from becoming bowed at its cutting edge, in order that the adenoid will always be cut away cleanly.

Another object of the invention is to provide an instrument for removal of adenoids which shall be so constructed as to be adapted to be sanitary while not excessively costly in manufacture or in maintenance, yet shall be strong, durable and economical in use.

50 With the above-mentioned and other objects in view, the invention consists in a novel instrument having a flexible cutting blade and a flexible guiding means for the blade of novel construction; and further, in the parts and combinations and arrangements of parts as hereinafter particularly

described and further defined in the appended claims.

Referring to the accompanying drawing,—Figure 1 is a side view of the improved instrument; Fig. 2 is an enlarged longitudinal sectional view clearly showing the structural features of the operative parts of the instrument; Fig. 3 is an opposite side view of the effective portion of the instrument on an enlarged scale; Fig. 4 is an enlarged cross-section showing guided working parts of the instrument; and Fig. 5 is a perspective view of the improved cutting knife and controlling guides therefor.

Similar reference characters on the different figures of the drawing indicate corresponding elements or features of construction herein referred to in detail.

In construction the instrument comprises a compound shaft which may be composed of a suitable number of parts, principally two main parts 1 and 2 having a thumb ring 3 at one end which has a swiveled connection with one of the main parts embodying a head member 4 on the ring mounted on a pintle 5 fixed on the end of one of the main parts. A screw 6 is inserted in one of the main parts and has a head 7 bearing against the opposite one of the main parts. The main parts are provided with rings 8 and 9 respectively into which two fingers of a hand of the operator are to be inserted in operation of the instrument.

A novel compound cutter is provided which comprises a cutter blade 10 and a stiffening plate 11 arranged against the blade at a suitable distance from the cutting edge of the blade and suitably guided in connection therewith, as by means of two transverse bars 12 suitably attached to the outer side of the plate 11, each bar being to the outer side of the plate 11, each bar being longer than the width of the plate and having guide members 13 on its opposite ends extending against the adjacent edges of the blade and the reinforcing plate, each member 13 having a guide lug 14 on its end extending opposite to the blade 10 at suitable distance therefrom. The blade 10 is slidably arranged on a guide plate 15 which is secured to the shaft part 1 by means of rivets 16, the plate being of suitable width to extend across the shaft part and project so as to be engaged by the guide lugs 14. The blade 10 and the plate 11 have suitable openings 17 to receive a control lug 18 which is carried integrally by the shaft part 2 so as to extend into a suitable groove in the opposite part 1. A fenestrum 19 of suitable curvature

has a suitable base part which is secured to the shaft part by means of rivets 20, the fenestrum being composed of flexible material and having an opening 21 therein, a terminal portion beyond the opening having a guard 22 on the inner portion thereof to receive and guard the extremity of the cutter.

10 A basket 23 is provided and arranged on the handle member 24 and connected thereto by means of a hinge pin 25 and is provided with a spring 26 tensioned appropriately to normally push the basket yieldingly toward the fenestrum so that it will co-operate therewith, the basket having side plates 27 suitably curved to contact 15 with the curved portion of the fenestrum.

An elastic plate 28 is arranged on the outer side of the frame part 1 and has a post 29 fixed thereto that extends through a suitable bearing in the part 1 and also into a longitudinal slot 20 in the part 2 and has a button 30 on its end suitably engaging the handle member 24 to hold it to the shaft, the plate having a lug 31 yieldingly inserted into a depression 32 provided for it in the part 1 of the shaft. The member 24 is 25 guarded against lateral movement by means of two side guides 33 carried by the part 2 of the shaft.

30 For attaining a higher degree of efficiency the projecting portion of the flexible cutter plate 10 is stiffened adjacent to its cutting edge by means of a cutter knife 34 suitably fixed thereto and having a sharp cutting edge portion 35.

35 In practical use the instrument is adjusted to the patient and manipulated by means of the rings provided on the shaft. The shaft is appropriately advanced so that the fenestrum yields adjustably to the contour wall of the individual and accordingly guides the cutter as it is advanced and accordingly guided to conform to the wall contour, resulting in completely 40 cutting away the adenoid tissue which is received in the co-operating basket.

45 What is claimed is:

45 1. An instrument for removal of adenoids having a flexible movable cutter, and a curved flexible guiding fenestrum along which said cutter moves, the flexibilities of said cutter and fenestrum being so interrelated that projection of the cutter along said fenestrum increases the 50 radius of curvature thereof.

2. An instrument for removal of adenoids having a flexible movable cutter, and a curved flexible guiding fenestrum along which said cutter moves, the flexibility of said fenestrum being adapted to permit changes in curvature thereof by its being pressed against a wall from which an adenoid is to be removed.

3. In an adenotome, a curved wall provided with an opening adapted to receive adenoid tissue, said wall consisting for the major portion 10 of its curvature of a single thickness of flexible material, a more flexible cutter blade projectable along the inner surface of said curved wall, and means for guiding said blade along said wall, said guiding means being non-resistant to 15 the flexing of said wall in its plane of curvature.

4. In an adenotome, a curved wall provided with an opening adapted to receive adenoid tissue, said wall consisting for the major portion 20 of its curvature of a single thickness of flexible material, a more flexible cutter blade projectable along the inner surface of said curved wall, and guiding members movable with said blade and embracing the side edges of said wall.

5. In an adenotome, an upwardly curved flex- 25 ible frame adapted to be flexed rearwardly by forward pressure against a surface from which an adenoid is to be removed whereby to lower the center of contact with such surface, a flex- 30 ible blade projectable in the plane of curvature of said frame across its opening and having a forward cutting edge, the flexing resistance of said blade being adapted to increase the radius of curvature of said frame whereby to raise the center of contact as said cutting edge travels 35 upwardly therealong.

6. In an adenotome, a curved flexible frame having an opening adapted to receive adenoid tissue, a flexible blade projectable in the plane of 40 said curvature across said opening and having a forward cutting edge, means reinforcing said blade over an area extending rearwardly from a point spaced from said cutting edge a distance less than the travel of said cutting edge, said 45 reinforcing means in co-operation with the blade being sufficiently resistant to flexing to increase the radius of curvature of said frame as it is projected therealong.

CHARLES R. STORZ. 50
